UNITED STATES PATENT OFFICE

2,089,466

WELL BIT

Alfred C. Catland, Alhambra, and William H. Maxwell, Beverly Hills, Calif., assignors to Globe Oil Tools Company, Los Nietos, Calif., a corporation of California

Application December 24, 1935, Serial No. 56,008

13 Claims. (Cl. 255—71)

This invention relates to a well drilling tool and relates more particularly to a roller rock bit. A general object of this invention is to provide an improved simplified and particularly efficient roller well drilling bit.

Another object of this invention is to provide a roller bit in which all of the several cutters are carried by a single readily removable carrier whereby the bit may be easily and quickly reconditioned by the replacement of the carrier and its cutters or by merely replacing the cutters following the removal of the carrier. The well bit of the present invention is adapted for use in fields remote from repair shops and transportation facilities because the cutters and the carrier for the cutters form a single compact unit that is easily transported and that may be quickly applied to the bit shank or head to recondition it for further use.

Another object of this invention is to provide a well bit in which the cutters are supported by the carrier to be particularly rapid and efficient in the drilling of a straight vertical bore.

Another object of this invention is to provide a roller bit of the character mentioned in which the cutter carrier may be easily removed from the head with simple tools and following the removal of the carrier the cutters may be easily removed from the carrier to permit the individual replacement of the cutters.

Another object of this invention is to provide a roller bit of the character mentioned that embodies novel and very dependable means for securing the cutter carrier to the shank or head.

Another object of this invention is to provide a roller rock bit that discharges the circulation fluid downwardly adjacent the bottom wall of the well to erode the formation and thus assist in the drilling action and to maintain the proper turbulence in the well bore.

Another object of this invention is to provide a roller bit of the character mentioned that embodies a choke or nozzle for discharging the circulation fluid downwardly adjacent the bottom wall of the well that assists in securing the cutter carrier to the head, definitely locates the carrier on the head and locks a cutter carrying pin against displacement.

A further object of this invention is to provide a roller rock bit of the character mentioned that is simple and inexpensive to manufacture and repair.

The various objects and features of our invention will be fully understood from the following 55 detailed description of a typical preferred form

and application of the invention, throughout which description reference will be made to the accompanying drawing, in which:

Fig. 1 is a side elevation of the bit provided by this invention with a portion broken away to appear in central vertical cross section. Fig. 2 is a central vertical detailed sectional view of the bit taken in a plane at right angles to the plane of sectioning of Fig. 1. Fig. 3 is a bottom elevation of the shank or head with the cutter carrier removed. Fig. 4 is a bottom elevation of the bit and Fig. 5 is a top or plan view of the carrier removed from the bit head.

The improved roller bit provided by this invention includes, generally, a shank or head 10, a removable carrier 11 on the head 10, inner cutters 12 and 13 on the carrier 11 and outer cutters 14 on the carrier 11.

The shank or head 10 constitutes the body of the bit and is adapted to be connected with a drilling string to be operated or rotated in a well. The upper portion of the head 10 is provided with means for connecting with the drilling string while the lower portion of the head is shaped to receive the carrier 11. In the typical form of the invention illustrated in the drawing, a tapered screw threaded pin 15 is provided at the upper end of the head 10 to facilitate the connection of the head with the drilling string. The intermediate or body portion of the head 10 may be cylindrical. In accordance with the invention the shank or head 10 is provided with two downwardly projecting legs 16. The legs 16 are preferably integral with the head 10 and are substantially diametrically opposite. The legs 16 project outwardly somewhat from the head 10 and their inner sides or surfaces 17 are inclined downwardly and outwardly. The invention provides a diametric slot or groove 18 in the lower end of the head 10. The groove 18 may extend from one side to the other of the head 10 and its opposite ends are preferably spaced substantially 90° from the legs 16. The groove 18 is dovetailed having downwardly and inwardly inclined or convergent side walls. The upper wall of the groove 18 is flat and substantially normal to the vertical axis of the bit.

The carrier 11 is preferably, though not necessarily, an integral member and is disposed at the lower end of the head 10 to rotatably support the cutters 12, 13, and 14. The carrier 11 is a spider-like element including a transverse or substantially horizontal web 19 and three horizontally spaced projections A, B, and C projecting downwardly from the web 18. When the carrier

11 is secured to the head 10 the web 19 is arranged below and is disposed longitudinally of the groove 18 so that the series of projections A, B, and C extends transversely or diametrically 5 between the legs 16. In accordance with the invention a dove-tailed tongue 20 is provided on the upper side of the web 19 to cooperate with the dove-tailed groove 18 in the head 10. The carrier 11 is arranged in position by introducing 10 the tongue 20 into the groove 18 and moving the carrier horizontally or transversely relative to the head 10. The upper end of the dove-tailed tongue 20 is flat and is adapted to cooperate with the upper wall of the groove 18 and one tapered 15 side of the tongue 20 is adapted to cooperate with one side wall of the groove. A gib or wedge 21 is inserted between the other side of the tongue 20 and the other side wall of the groove 18 to lock or secure the tongue in the groove. The gib 20 or wedge 21 is suitably tapered and is adapted to be driven in place to tightly lock the tongue 20 in the groove 18. Following the wedging or driving in of the wedge 21 its opposite end portions which 25 extend from opposite sides of the head 10 may be peened over to prevent loss or displacement of the wedge. When the tongue 20 is properly locked in the groove 18 its upper end bears against the upper wall of the groove and the upper side of the web 19 bears upwardly on the bottom of the 30 head 10 as at 22. The tongue 20 dependably locked in the groove 18, as just described, securely and rigidly connects the carrier 11 with the head 10.

The projections A, B, and C constitute the cutter carrying parts of the carrier 11. The projection A is preferably located at or adjacent one side of the central vertical axis of the bit, the projection B is spaced outwardly from the projection A and is located at the same side of the 40 said vertical axis as the projection A while the projection C is spaced outwardly from the projection A at the other side of the said axis. The projection A is yoked or provided at its lower end with a central notch 23 and two laterally projecting wings 24. The wings 24 have downwardly and outwardly inclined bearing surfaces 25 which oppose and are substantially parallel with the inner surfaces 17 of the legs 16. Pins 26 project outwardly from the bearing surfaces 17 and 25 and 50 their outer ends may bear on the surfaces 17 of the legs 16. Screws 9 may be passed outwardly through longitudinal openings 8 in the pins 26 and threaded into openings 7 in the legs 16 to connect the pins 26 with the legs. The screws 9 assist in attaching the carrier 11 to the head 10. The projection B preferably has a flat vertical inner side provided with a recessed bearing surface 27. The projection C is comparatively thick and may project outwardly beyond the peripheral 60 edge of the head 10. The inner side of the projection C is preferably substantially vertical and is provided with a recessed bearing surface 28.

The inner cutters 12 and 13 are provided to act on and cut away the earth formation at the inner 65 portion of the bottom wall of the well. The cutter 12 is rotatably mounted between the projections A and C while the cutter 13 is rotatably mounted between the projections A and B. The invention provides a single, simple means for rotatably supporting the two inner cutters 12 and 13. A removable pin 29 is introduced inwardly through a substantially horizontal opening 30 in the leg B and has a reduced inner portion 31 threaded into an opening 32 in the projection 70 C. The threaded portion 31 of the pin being re-

duced provides an annular shoulder 33 on the pin.

The head of the pin 29 is recessed in the outer side of the leg B.

The cutter 12 which is rotatably supported on the pin 29 between the projections A and C is a frusto-conical cutter having a tapered periphery provided with spaced cutting teeth 34. The cutter 12 is positioned with its small end facing the projection A. A roller bearing 35 may rotatably support the cutter 12 on the pin 29. A thrust washer 36 is arranged on the reduced portion 31 of the pin 29 between the surface 28 of the projection C and the shoulder 33 of the pin. The washer 36 is adapted to receive outward thrusts from the end of the cutter 12. The thrust washer 36 has shouldered cooperation with the projection C at 37 which holds it against rotation. The cutter 12 rotatably mounted as just described projects downwardly below the projections A and C to act on the earth formation and follow an 20 annular path immediately adjacent the center of the well bore.

The cutter 13 is rotatably supported on the pin 29 in the space between the projections A and B. The cutter 13 is frusto-conical and is arranged 25 with its small end toward the projection A. Peripheral cutting parts 38 are provided on the cutter 13 and are adapted to project downwardly beyond the lower ends of the projections A and B to act on the formation at the bottom of the bore. A roller bearing 39 may rotatably support the cutter 13 on the pin 29. A thrust washer 40 is arranged on the pin 29 between the outer end of the cutter 13 and the bearing surface 27 of the projection B. The washer 40 has shouldered engagement with the projection B at 41 which holds it against turning on the pin 29. A spool or spacer 42 is provided on the pin 29 between the inner opposing ends of the cutters 12 and 13. The spacer 42 maintains the cutters 12 and 13 40 in their proper positions and its opposite ends are adapted to receive inward thrusts from the cutters. In practice the spacer 42 passes through the notch 23 with freedom or clearance. The cutter 13 mounted as just described has an annular path of engagement with the earth formation which surrounds and overlaps that of the cutter 12. The cutters 12 and 13 in being frusto-conical and in having their small ends facing inwardly form and act on a conical mound on the bottom wall of the well bore which operates to center the bit during drilling.

The outer cutters 14 are rotatably supported on the pins 26 to project downwardly beyond the lower ends of the legs 16 and act on the formation at the outer portion of the well bore to cut the bore to size. The cutters 14 are substantially frusto-conical roller cutters rotatably supported on the inclined pins 26 to have their small ends facing inwardly. Peripheral cutting teeth 43 are provided on the cutters 14. The inner or small ends of the cutters 14 are adapted to bear on the thrust surfaces 25 of the wings 24. Thrust washers 44 are arranged on the pins 26 between the outer ends of the cutters 14 and the inner surfaces 17 of the legs 16. The washers 44 are provided with lugs 45 which engage the lower ends of the legs 16 to hold the washers against turning. Roller bearings 46 may be provided to rotatably support the outer cutters 43 on the downwardly and inwardly inclined pins 26. The outer ends of the cutting teeth 43 are bevelled or cut away to be substantially vertical as they come into engagement with the earth formation and thus properly cut the bore to 75

gauge. The frusto-conical cutters 14 rotating about downwardly and inwardly inclined axes follow annular paths surrounding and overlapping the path of the cutter 13 and their teeth 43 are substantially horizontal as they successively come into cutting engagement with the formation.

The invention provides a novel nozzle or fluid discharge member 48 which discharges the circulation fluid downwardly against the formation at the bottom of the bore and in addition to this function locks the pin 29 against unthreading, assists in securing the carrier 11 to the head 10 and definitely locates the carrier on the head. A central bore or socket 49 extends downwardly in the head 10 from the upper end of the pin 15 and a passage or port 50 joins the lower end of the socket. The projection C of the carrier 11 has a downwardly and outwardly inclined opening 51 which is longitudinally aligned with the port 50. The opening 51 extends to the lower end of the projection C and its lower portion is enlarged providing a downwardly facing annular shoulder 52. The fluid discharge member 48 is an elongate part passed through the opening 51 and having its upper end threaded into the lower portion of the port 50. The lower portion 48a of the member 48 is of enlarged diameter and is adapted to bear upwardly against the shoulder 52 when the member 48 is finally tightened into the port 50. The member 48 is provided with a central longitudinal fluid opening 53 whose upper end communicates with the port 50. A polygonal socket 54 is provided at the lower end of the opening 53 to receive a wrench or the like for threading the member 48. The lower end of the member 48 is disposed at the lower end of the projection C so that the fluid discharged from the member impinges directly against the formation at the bottom of the well to have an eroding action.

The threading of the fluid discharge member 48 into the port 50 definitely locates the carrier 11 with respect to the head 10 and the engagement of the enlargement 48a with the shoulder 52 may assist in securing the carrier 11 to the head 10. In accordance with the invention the opening 32 receiving the threaded portion 31 of the pin 29 joins the lower enlarged part of the opening 51. The inner end of the pin 29 is inclined and is shaped or grooved to be engaged by the enlarged portion 48a of the fluid discharge member 48. This engagement of the portion 48a of the discharge member with the pin 29 locks the pin 29 against unthreading. Thus the fluid discharge member 48 serves to discharge the circulation fluid downwardly from a point immediately adjacent the bottom of the well, definitely locates the carrier 11 with respect to the head 10, assists in securing the carrier to the head and locks the cutter carrying pin 29 against rotation and unthreading.

The invention provides downwardly and outwardly inclined fluid ports 56 in the head 10 which extend downwardly from the socket 49 to discharge into the spaces between the legs 15 and the projection A. The fluid discharged from the ports 56 impinges against the outer cutters 14 to effectively flush them. Ports 57 extend downwardly through the head 10 from the lower end of the socket 49 to the upper wall of the dove tailed groove 18. Discharge ports 58 are provided in the web 19 of the carrier 11 to communicate with the lower ends of the ports 57

and to discharge circulation fluid downwardly against the inner cutters 12 and 13.

In operation the shank or head 10 is connected with the lower end of a drilling string which is to be rotated and fed downwardly in the well. As the bit is rotated the inner cutters 12 and 13 take annular paths across the inner portion of the bottom wall of the well while the outer cutters 14 pursue an annular course surrounding the path of the cutter 13. The outer cutters 14 also act on the side wall of the well to cut the well to gauge. Thus the cutters 12, 13, and 14 act on substantially the entire bottom wall of the well. The frusto-conical inner cutters 12 and 13 operate against an inclined shoulder or shoulders of the earth formation and thus operate to center the bit in the well. The cutters 12, 13, and 14 are dependably supported for independent rotation. The circulation fluid discharged downwardly from the discharge member 48 adjacent the bottom wall of the well and adjacent the outer wall of the well is effective in eroding the formation and producing the necessary turbulence in the bottom of the well. The dove-tailed tongue 20 tightly wedged in the groove 18 by the wedge 21 dependably secures the carrier 11 to the head 10.

When it becomes necessary or desirable to replace the cutters 12, 13, or 14 or the carrier 11 the tool is withdrawn from the well and the carrier is removed from the head. To remove the carrier 11 from the head 10 one or both of the peened over ends of the gib or wedge 21 are straightened out or cut off and the wedge 21 is driven from the groove 18. The pins 9 are unthreaded from the openings 7 to free or disconnect the pins 26 from the legs 16. The fluid discharge member 48 is unthreaded from the port 50 and removed whereupon the carrier 11 may be moved transversely relative to the head 10 to disengage its tongue 20 from the groove 18. The removal of the member 48 from the opening 51 permits the easy unthreading of the cutter carrying pin 29 so that the cutters 12 and 13 may be easily removed from the carrier 11. Following the removal of the carrier 11 from the head 10 the outer cutters 14 may be readily slid from the pins 26. If found necessary a new or replacement carrier 10 provided with new cutters 12, 13, and 14 may be readily assembled on the head 10. Where the carrier 11 is not excessively worn it may be provided with new or replacement cutters 12, 13, and 14 and re-attached to the head 10 to condition the bit for further use. The carrier 11 provided with the cutters 12, 13, and 14 or handled separately from the cutters is a simple compact unit that may be easily transported for reconditioning the bit. The fluid discharge member 48 may be replaced when it becomes worn or eroded through the action of the mud laden fluid.

Having described only a typical preferred form and application of our invention, we do not wish to be limited or restricted to the specific details herein set forth, but wish to reserve to ourselves any variations or modifications that may appear to those skilled in the art or fall within the scope of the following claims.

Having described our invention, we claim:

1. A well bit comprising a head having spaced legs on its lower end, a carrier at the lower end of the head between the legs, projections on the lower end of the carrier, roller cutters rotatably supported between the projections, roller cutters rotatably supported between the legs and the

projections, and a tongue and groove connection between the head and carrier, the longitudinal axis of the tongue and groove of said connection being transverse of the head.

5. 2. A well bit comprising a head having spaced legs on its lower end, a carrier at the lower end of the head between the legs, roller cutters carried by the carrier, roller cutters rotatably supported between the legs and the projections, and 10 a tongue and groove connection between the carrier and head, said connection comprising a diametric dove-tailed groove in the lower end of the head, and a dove-tailed tongue on the carrier introduced into the groove by relative transverse movement between the head and carrier.
3. A well bit comprising a head having spaced legs projecting from its lower end, a carrier between the legs at the lower end of the head having projections on its lower end, a tongue and groove connection between the head and carrier, roller cutters, and means rotatably supporting the cutters between the legs and the projections.
4. A well bit comprising a head having spaced legs projecting from its lower end, a carrier between the legs at the lower end of the head having projections on its lower end, a tongue and groove connection between the head and carrier, screws connecting the projections and legs, and roller cutters rotatably supported between the legs and projections.
5. A well bit comprising a head, a single carrier arranged diametrically across the lower end of the head, cutters on the carrier, a tongue and groove connection between the head and carrier made up by relative transverse movement between the head and carrier, and a fluid discharge member cooperating with the head and carrier to hold them against relative transverse movement in both directions in the diametric plane of the carrier.
6. A well bit comprising a head, a carrier at the lower end of the head, cutters on the carrier, a tongue and groove connection between the head and carrier made up by relative transverse movement between the head and carrier, there being a fluid port in the head and an opening in the carrier, and a fluid discharge member arranged in the port and opening to hold the head and carrier against relative transverse movement and conducting fluid from the port to discharge it from the carrier.
7. A well bit comprising a head having downwardly projecting legs, a carrier at the lower end of the head between the legs having projections extending toward the legs, cutters rotatably supported between the legs and projections, a tongue and groove connection between the head and carrier made up by relative transverse movement between the head and carrier, and means connecting the legs and projections to prevent such relative transverse movement.
8. A well bit comprising a head having downwardly projecting legs, a carrier at the lower end of the head between the legs having projections extending toward the legs, cutters on the carrier, a tongue and groove connection between the head and carrier assembled by relative transverse

movement between the head and carrier, and means detachably connecting the legs and projections to prevent such relative transverse movement.

9. A well bit including a head, a carrier at the lower end of the head, spaced legs on the lower end of the carrier having aligned openings, a pin passed through the opening of one leg and threaded into the opening of another leg, cutters supported by the pin, a tongue and groove connection between the head and carrier assembled by relative transverse movement between the head and carrier, there being a fluid port in the head and an opening in said other leg registering with the port, and a fluid discharge member in the opening cooperating with the port to receive fluid therefrom and to prevent relative transverse movement between the head and carrier and cooperating with the pin to prevent unthreading of the same.

10. A well bit comprising a head, a carrier at the lower end of the head, cutters on the carrier, a tongue and groove connection between the head and carrier made up by relative transverse movement between the head and carrier, there being a fluid port in the head and an opening in the carrier aligned with the port, and a fluid discharge member extending through the opening and threaded into the port to bear upwardly against the carrier to assist in securing the carrier to the head and to prevent relative transverse movement between the head and carrier.

11. A well bit including two elements, one a head, the other a cutter carrier, there being a dove-tailed groove in one element, a dove-tailed tongue on the other element inserted in the groove by relative transverse movement between the elements to connect the elements, there being aligned openings in the elements, and a fluid discharge member threaded into one opening and 40 cooperating with the other opening to lock the elements against relative transverse movement.

12. A well bit comprising a head having a dove-tailed groove in its lower end, legs projecting from the lower end of the head, a carrier, a dove-tailed tongue on the carrier received in the groove to connect the carrier and head, spaced projections on the carrier, pins on one of the projections extending outwardly to the legs, cutters rotatable on the pins, means connecting the pins 50 and legs, and cutters rotatably supported between the said projection and the other projections.

13. A well bit comprising a head having a dove-tailed groove in its lower end, legs projecting from the lower end of the head, a carrier, a dove-tailed tongue on the carrier received in the groove to connect the carrier and head, spaced projections on the carrier, pins on one of the projections extending outwardly to the legs, 60 cutters rotatable on the pins, means connecting the pins and legs, a pin extending between and carried by the other projections, and roller cutters on said pin.

ALFRED C. CATLAND.
WILLIAM H. MAXWELL.
